UNITED STATES PATENT OFFICE.

CHARLES VERBSKY, OF CLEVELAND, OHIO.

SWIMMING APPARATUS.

Application filed November 28, 1924. Serial No. 752,707.

To all whom it may concern:

Be it known that I, CHARLES VERBSKY, a citizen of the United States, residing at Cleveland, in the county of Cuyahoga and

5 State of Ohio, have invented certain new and useful Improvements in Swimming Apparatus, of which the following is a specification.

This invention relates to improvements in 10 swimming apparatus having for an object to provide a compactly built mechanism which may be readily attached to the human body and be operated through a natural walking movement of the limbs.

15 Another object is to provide an apparatus of this character wherein the apparatus is so positioned as to permit use of the calf and thigh muscles of the body in operating the propeller mechanism which pulls rather than 20 pushes the body through the water.

A further object is to provide a swimming 25 apparatus including a screw propeller and means for preventing radial throw of the water by the propeller, thereby materially increasing the pulling power of the mechanism.

It is likewise an object to provide a compactly constructed swimming apparatus which will offer a minimum amount of 30 resistance to movement through the water.

Other objects will be in part obvious and in part pointed out hereinafter.

In order that the invention and its mode 35 of operation may be readily understood by persons skilled in the art, I have in the accompanying illustrative drawings, and in the following detailed description based thereon set out one possible embodiment of the same.

40 Figure 1 is a perspective view of the complete swimming apparatus;

Figure 2 is a side elevation thereof;

Figure 3 is a vertical longitudinal sectional view, the propeller and adjacent parts 45 being shown in elevation;

Figure 4 is a detail sectional view taken substantially on the line 4—4 of Figure 2;

Figure 5 is a sectional view taken on the line 5—5 of Figure 4, and

50 Figure 6 is a detail sectional view showing a modified structure of the propeller.

Having more particular reference to the drawings throughout which similar characters of reference designate similar parts 55 this improved swimming apparatus comprises an open ended shell or protector 10

which is preferably made up of a rust proof material and has its upper wall cut away at its ends so as to afford reasonable comfort to the wearer. A pair of attaching 60 strips 11 is secured to the forward underside of the shell and as shown in Figure 1 provide for securing the shell to the body of the wearer. It may be here stated that this apparatus is designed to be placed upon 65 the chest of the wearer, this positioning providing for a maximum degree of efficiency.

Arranged within the shell or protector 10 is a pair of longitudinally spaced transverse bars 12 whose ends are riveted or otherwise 70 secured to opposite sides of said shell. A shaft 13 is arranged centrally and longitudinally in the shell and is provided at each end with oppositely directed substantially cone shaped heads 14 which are so 75 shaped in order that they will offer a minimum amount of resistance to passage of the apparatus through the water. One of these substantially cone shaped heads 14 has its apex rotatably fitted into a socket 15 carried 80 by the forward transverse bar 12, while the other head is provided with a substantially cone shaped socket adapted to receive a bearing screw 16 which is threaded into a bearing formed upon the rear transverse bar 12 85 as shown in Figures 3 and 4. This screw provides for ready separation of the parts.

A screw propeller 17 is arranged adjacent the front cone shaped head 14 and is rotatable with said head and shaft. This propeller may be of any preferred construction, or as shown in Figure 6, made up of individual blades each carrying an attaching ear.

In order to provide for rotation of the propeller in one direction I arrange adjacent the rear cone shaped head 14, a pair of spaced sheaves 18 which as shown in Figure 5 carry pawls or the like 19 which are engageable in notches 20 circumferentially spaced about the shaft and cause it to rotate 95 only when they are moved in one direction. These sheaves 18 are designed for oscillation through passing around the same, cords 21 or the like, corresponding ends of the cords being connected together as shown in Figures 1 and 2. These cords as illustrated in Figure 4 are passed over pulleys 22 and thence rearwardly as is clear in Figure 1. The free ends of these cords are attached to web strips 23 which provide for attachment 100 of the cords to the feet of the person using the apparatus. The pulleys 22 over which

the cords 21 pass are attached to longitudinal brackets 24 whose rear ends are riveted or otherwise fastened to the rear transverse frame bar 12. As illustrated in Figure 4 the 5 brackets are braced by means of stay rods 24 whose outer ends are securely fastened to the shell or protector.

In using this apparatus it is strapped to the body, and the web strips 23 are secured 10 to the feet of the operator. In attaching this apparatus the narrow portion of the casing 10 is arranged upon the lower portion of the user's chest and the straps 11 are carried over the shoulders in substantially the same 15 manner as a pair of suspenders, the exception being that the back portions of the straps are carried downwardly and forwardly for attachment to the sides of the casing. An ordinary walking movement of 20 the legs will alternately pull upon the cords 18 and operate first one of the sheaves 18 and then the other, thus intermittently engaging the pawls 19 with the notches 20 formed in the propeller carrying shaft 13. 25 It is obvious that this operation will cause a continued rotation of the propeller in one direction and consequently cause a forward movement of the person using the apparatus. As has been previously stated the provision 30 of a shell about the propeller prevents radial throw of the water by the propeller and consequently gives a greater thrust as is quite obvious.

The several parts are so designed as to 35 offer a minimum amount of resistance to the passage of water and as shown in Figure 3 a substantially cone shaped body 26 is fixed to rotate with the shaft 13 and incidentally minimizes resistance that the sheaves 18 40 might otherwise offer to the passage of water.

Manifestly, the construction shown is capable of considerable modification and such

modification as may fall within the scope of my claims, I consider within the spirit of my invention.

45

I claim:

1. A swimming apparatus comprising an open ended shell, an open frame arranged in the shell, a rotatable shaft mounted in the frame, and having cone shaped elements at 50 each end, a screw propeller fixed to the shaft, a pair of sheaves loosely arranged upon the shaft and formed to rotate the shaft in one direction, and a pair of cords extending about the sheaves and designed to be attached to the feet of a person using the apparatus.

2. A swimming apparatus comprising, an open ended shell, a shaft centrally and 60 rotatably mounted in the shell, a screw propeller fixed to the forward end of the shaft, a pair of spaced sheaves arranged upon the shaft rearwardly of the propeller, clutch mechanism arranged to interconnect the sheaves and shaft at times, and a pair of 65 cords extending about the sheaves and designed for attachment to the feet of a person using the apparatus.

3. A swimming apparatus comprising, an open ended shell, a rotatable shaft arranged 70 centrally and longitudinally in the shell, a screw propeller fixed to the forward end of the shaft, a pair of spaced sheaves arranged upon the shaft, means interengaging the shaft and sheaves at times, pairs of pulleys 75 arranged at opposite sides of the sheaves and in spaced relation thereto, and operating cords extending about the sheaves and through the pulleys and designed for attachment to the feet of a person using the apparatus.

In testimony whereof, I affix my signature.

CHARLES VERBSKY.
